DESIGN FOR A SLIP

Alfred S. Farmer, New York, N. Y.

Application March 5, 1940, Serial No. 90,689

Term of patent 3½ years

To all whom it may concern:

Be it known that I, Alfred S. Farmer, a citizen of the United States of America, residing in New York city, in the Borough of Manhattan, county and State of New York, have invented a new, original, and ornamental Design for a Slip, of which the following is a specification, reference being had to the accompanying drawing, forming part thereof, wherein,

I claim:

The ornamental design for a slip, substantially as shown.

ALFRED S. FARMER.
